DEVICE FOR CONNECTING SCAFFOLD POLES AND THE LIKE

Isaac Rich, Hassocks, England

Application November 18, 1932, Serial No. 643,219, and in Great Britain November 23, 1931

11 Claims. (Cl. 189—26)

This invention relates to improvements in and connected with devices for connecting or clamping transverse or horizontal scaffold poles to vertical poles, of the type in which the device is in the form of a U-shaped metal member across the limbs of which is fitted a plate through which is threaded a member adapted to apply pressure so as to draw transversely related poles towards each other, one of the poles being engaged in the bend of the U-shaped member and the other in slots or apertures in the limbs of the U-shaped member. One object of this invention is to obviate loss of the said plate. Further in the type of device in question it is desirable to employ a distance piece between the points of intersection of the two poles passing through the U-shaped metal member, and frequently objection is raised to these distance piece members being left lying about so that they become lost or are untidy, or further are liable to cause injury by falling particularly when scaffolding is being disassembled. Another object of the present invention is to obviate this objection.

According to the present invention a device of the type set forth comprises a U-shaped metal member slotted in its limbs to receive a pole and adapted to receive another pole in its intermediate portion at right angles to the aforementioned pole, a metal plate being pivotally connected to one of said limbs and having a set screw threaded through it, the said plate being free to be swung into lateral recesses in the slots of said limbs so as to bridge said limbs to constitute an abutment opposed to the bend of the U-shaped member.

A further characteristic feature of the present invention is the provision of a supplementary plate or a distance piece in addition to the metal plate above mentioned, this supplementary plate or distance piece being relatively movably connected to the said U-shaped member so that it will not free itself therefrom and being located so that it can be placed between the two poles and being shaped so as to provide a substantial surface contact with both said poles.

In order that my invention may be clearly understood and readily carried into effect I have appended hereto one sheet of drawing illustrating an embodiment thereof, and wherein:—

Fig. 1 is a side elevation view.

Fig. 2 is a plan view.

Fig. 3 is a section on the line 3a 3a of Fig. 1, and

Fig. 4 is a section on the line 4a 4a of Fig. 1.

Referring to the drawing the embodiment illustrated comprises a U-shaped metal member 1 formed with wide limbs which are slotted as at 2 to receive a pole 3, the other pole 4 being engaged in the bend of the U-shaped member in well known manner, set screws 18 if desired being threaded through the member 1 near its bend to engage the pole 4. A distance piece 15 is interposed between the two poles across the limbs of the member 1.

Each of the slots 2 is laterally enlarged as at 5 at the outer end to provide abutments 6 against which a metal plate or bar 7 can abut, this plate or bar being formed with a central boss 8 through which is threaded a set or binding screw 9 formed with an apertured head 10 in which can be inserted a tommy bar to enable the screw 9 to be turned so as to apply a high pressure to the pole 3. If desired a pressure plate 7a loosely hinged in slotted lugs 8a on the plate 7 may be interposed between the end of the screw 9 and the pole 3.

The plate or bar 7 is preferably of rectangular form and to ensure it always being ready for use it is pivotally connected to the member 1, a suitable method of connection comprising a finger or lug 11 integral with one corner of the plate or bar 7 and apertured to receive a rivet 12 somewhat slackly fitted in the lug 11 and a pair of lugs 13 formed on the outer face of one of the limbs of the U-shaped member 1. To enable the plate or bar 7 to be swung clear of the abutments 6 the lateral recesses 5 on the side of the slots 2 remote from the recess 5 contiguous to the pivoted support of the plate or bar 7 is prolonged to provide the necessary clearance 5a in one limb of the U-shaped member, the corner of the plate or bar 7 diagonally opposite its pivoted corner being cut at an angle or rounded as at 14 (Fig. 3) to clear the appropriate recess 5a.

The distance piece 15 above referred to is so mounted on the U-shaped member 1 that it can be readily located between the poles 3 and 4 and will equally readily free itself from engagement with the pole 4 when disassembling scaffolding. The preferred method of connecting this distance piece 15 to the member 1 is to form it at one end with a sleeve 16 through which a pivot pin 17 is passed this pivot pin being secured at its ends in a pair of lugs 18a formed on one side of the U-shaped member 1 near the inner corners of the slot 2 of said side. The distance piece is a metal plate dimensioned so that it can swing about the pivot pin 17 through the

slot 2 to the transverse position shown in Fig. 2 extending across the sides of the U shaped member 1 and pressed between the two poles 3 and 4.

To ensure a good gripping action on the poles 5 the distance piece 15 is arcuately shaped in its longitudinal dimension to partly embrace the pole 4 as indicated at 15a, and its free end is bent away from the pole 4 or thickened as indicated at 19 such free end being arcuately recessed in its edge, this arcuate recess being indicated by the reference numeral 20 (Fig. 4) and radiused so as to partly embrace the pole 3. It is also preferred to increase the thickness of this distance piece 15 at its pivoted end as indicated by the reference numeral 21 and to arcuately recess as at 22 the face of this part which engages the pole 3 to co-operate with the arcuate recess 20 in gripping such pole.

It will be apparent that by means of my present invention not only is the security and efficiency of the pole connector increased by reason of the configuration and location of the distance piece 15, but also there is no risk of the various parts falling loose.

25 I claim:—

1. In a device for connecting scaffold poles a U shaped metal member, slots in its limbs to receive a pole in a direction transverse to another pole adapted to be received in the bend of the U shaped member, a plate pivoted to one of said limbs, a set screw threaded through said plate and lateral recesses in the opposed edges of said slots adapted to receive the said pivoted plate by swinging said plate into such recesses so as to bridge the limbs of the U shaped metal member.

30 2. A device for connecting scaffold poles comprising a U shaped metal member, a plate hinged to one limb of said member and adapted to bridge both of the limbs of the U shaped member, slots carried through the free ends of said limbs adapted to receive a pole, another pole being adapted to be received in the bend of the U shaped member, abutments in the opposed edges of said slots against which said plate is adapted to be outwardly pressed, and a set screw threaded through said plate adapted to be screwed towards the pole in said slots.

35 3. A device for connecting scaffold poles comprising a U shaped metal member, a plate hinged to one limb of said member and adapted to bridge both of the limbs of the U shaped member, slots carried through the free ends of said limbs adapted to receive a pole, another pole being adapted to be received in the bend of the U shaped member, abutments in the opposed edges of said slots against which said plate is adapted to be outwardly pressed, a set screw threaded through said plate adapted to be screwed towards the pole in said slots, and a distance piece adapted to be interposed between the two poles relatively movably permanently connected to the U shaped member.

40 4. A device for connecting transversely related scaffold poles comprising a U shaped member and a plate inseparably but relatively movably connected to each other, said plate bridging the limbs of said U shaped member, abutments in said limbs near their free ends against which said plate is adapted to be outwardly pressed, a pressure applying member threaded through said plate, and a distance piece adapted to be interposed between the two poles relatively movably permanently connected to the U shaped member.

45 5. In a device for connecting scaffold poles a U shaped metal member, slots in its limbs to re-

ceive a pole in a direction transverse to another pole adapted to be received in the bend of the U shaped member, a plate pivoted to one of said limbs, a set screw threaded through said plate and lateral recesses in the opposed edges of said slots adapted to receive the said pivoted plate by swinging said plate into such recesses so as to bridge the limbs of the U shaped metal member, a supplementary plate or distance piece being relatively movably connected to the said U shaped member so that it will not free itself therefrom and being located so that it can be placed between the two poles and being shaped so as to provide a substantial surface contact with both said poles.

50 6. A device for connecting scaffold poles comprising a U shaped metal member, a plate hinged to one limb of said member and adapted to bridge both of the limbs of the U shaped member, slots carried through the free ends of said limbs adapted to receive a pole, another pole being adapted to be received in the bend of the U shaped member, abutments in the opposed edges of said slots against which said plate is adapted to be outwardly pressed, a set screw 100 threaded through said plate adapted to be screwed towards the pole in said slots, and a distance piece plate pivoted to one limb of the U shaped member between the said set screw carrying plate and the bend of the U shaped member and adapted to be located between the two poles and to be swung about its pivot through one of said slots.

55 7. In a device for connecting scaffold poles a U shaped metal member, slots in its limbs to receive a pole in a direction transverse to another pole adapted to be received in the bend of the U shaped member, a plate pivoted to one of said limbs, a set screw threaded through said plate, lateral recesses in the opposed edges of said slots 110 adapted to receive the said pivoted plate by swinging said plate into such recesses so as to bridge the limbs of the U shaped metal member, and a distance piece member relatively movably carried by said plate and adapted to lie between the pole in said slots and said plate.

60 8. A device for connecting transversely related scaffold poles comprising a U shaped member and a plate inseparably but relatively movably connected to each other, slots in the limbs of said 115 U-shaped member to receive a pole in a direction transverse to another pole adapted to be received in the bend of the U-shaped member said plate bridging the limbs of said U shaped member, abutments in said limbs near their free 120 ends against which said plate is adapted to be outwardly pressed, a pressure applying member threaded through said plate, and a distance piece member relatively movably carried by said plate and adapted to lie between the pole in said 125 slots and said plate.

65 9. In a device for connecting scaffold poles a U shaped metal member, slots in its limbs to receive a pole in a direction transverse to another pole adapted to be received in the bend of the 130 U shaped member, a plate pivoted to one of said limbs, a set screw threaded through said plate and lateral recesses in the opposed edges of said slots adapted to receive the said pivoted plate by swinging said plate into such recesses so as to 135 bridge the limbs of the U shaped metal member, a supplementary plate or distance piece being relatively movably connected to the said U shaped member so that it will not free itself therefrom and being located so that it can be 140 145 150

placed between the two poles and being shaped so as to provide a substantial surface contact with both said poles, and a distance piece member pivoted to said set screw carrying plate and adapted to lie between the pole in said slots and the set screw.

10. A device for connecting scaffold poles comprising a U shaped metal member, a plate hinged to one limb of said member and adapted to bridge both of the limbs of the U shaped member, slots carried through the free ends of said limbs adapted to receive a pole, another pole being adapted to be received in the bend of the U shaped member, abutments in the opposed edges 15 of said slots against which said plate is adapted to be outwardly pressed, a set screw threaded through said plate adapted to be screwed towards the pole in said slots, a distance piece adapted to be interposed between the two poles 20 relatively movably permanently connected to the U shaped member, and recesses in the pole engaging face and ends of said distance piece adapted to partly embrace the two poles.

11. A device for connecting scaffold poles com-

prising a U shaped metal member, a plate hinged to one limb of said member and adapted to bridge both of the limbs of the U shaped member, slots carried through the free ends of said limbs adapted to receive a pole, another pole being adapted to be received in the bend of the U shaped member, abutments in the opposed edges of said slots against which said plate is adapted to be outwardly pressed, a set screw threaded through said plate adapted to be screwed towards the pole in said slots, and a distance piece plate pivoted to one limb of the U shaped member between the said set screw carrying plate and the bend of the U shaped member and adapted to be located between the two poles and to be swung about its pivot through one of said slots, said distance piece plate being arcuately recessed in one face in a direction parallel to the said pivot pin to partly embrace one pole and arcuately recessed at its free edge and also at its pivoted edge to partly embrace the other pole.
